UNITED STATES PATENT OFFICE.

G. RALSTON AYRES, OF PHILADELPHIA, PENNSYLVANIA, ASSIGNOR TO HIMSELF, WILLIAM MONTGOMERY AYRES, AND LOUIS H. AYRES, ALL OF SAME PLACE.

DESIGN FOR A HORSE-BLANKET.

SPECIFICATION forming part of Design No. 17,806, dated October 25, 1887.

Application filed April 23, 1887. Serial No. 235,943. Term of patent 14 years.

To all whom it may concern:

Be it known that I, G. RALSTON AYRES, a citizen of the United States, and a resident of Philadelphia, Pennsylvania, have invented a new and original Design for a Horse-Blanket, of which the following is a specification.

My design is fully shown in the accompanying drawings, in which—

Figure 1 is a side view of a horse-blanket embodying the design; and Fig. 2, an enlarged view, showing more clearly the character of the stripes composing the pattern.

The blanket has the curved back border, *a*, curved neck border *b*, front and rear borders, *d* and *f*, and bottom border, *g*, and the body of the blanket is striped transversely, the stripes extending from the curved back and neck borders to the bottom border of the blanket parallel with the front and rear borders.

20 The pattern consists of wide composite stripes *h* and intervening narrow stripes, *i*, each composite stripe having a narrow central stripe, *n*, and wider side stripes, *m*, said stripes *m* and *n* being of strongly-contrasted colors or 25 shades, so that the narrow central stripe forms a prominent feature of the pattern.

I claim—

1. The within-described design for a pattern

for horse-blankets, said design consisting of the wide composite stripes *h* and intervening narrow plain stripes, *i*, said composite stripe having a central narrow stripe, *n*, and wider side stripes, *m*, the color or shade of which is in strong contrast with that of the central stripe, all substantially as described and shown. 30

2. The within-described design for a horse-blanket, said design consisting of the curved back and neck borders, the front, rear, and bottom borders, and the body having a pattern composed of stripes extending from the 40 back and neck borders to the bottom border parallel with the front and rear borders, said striped pattern consisting of wide composite stripes *h* and intervening narrower plain stripes, *i*, the composite stripe having wide 45 side stripes, *m*, and narrow central contrasting stripe, *n*, all substantially as described and shown. 35

In testimony whereof I have signed my name to this specification in the presence of two subscribing witnesses.

G. RALSTON AYRES.
